UNITED STATES PATENT OFFICE.

JOHN FRAZIER, OF SEARCY, ARKANSAS.

STEAM STEERING APPARATUS.

SPECIFICATION forming part of Letters Patent No. 271,326, dated January 30, 1883.

Application filed July 10, 1882. (No model.)

To all whom it may concern:

Be it known that I, JOHN FRAZIER, a citizen of the United States, residing at Searcy, in the county of White and State of Arkansas, 5 have invented a new and useful Improvement in Steam Steering Apparatus, of which the following is a specification.

The object of my invention is to provide means whereby to quickly and accurately operate the rudder of a vessel and secure the same in any position to which it is set. This object I effect by combining with said rudder an operating-engine and a peculiar valve device, as fully described hereinafter. The said 15 engine and valve are adapted for application to other purposes.

In the drawings, Figure 1 is a perspective view showing an engine with my improved valve device and connections with the rudder of a vessel. Fig. 2 is a perspective view showing the portion of the valve-operating lever extending into the pilot-house. Fig. 3 is a perspective view of the cylinder and valve-chest. Fig. 4 is a perspective view of the valve. Figs. 25 5 and 6 are cross-sections of the valve, respectively, on the lines 11 12 13 14, Fig. 4. Fig. 7 is a perspective view of the valve-cap, and Fig. 8 is a view showing a modification.

Z represents the shaft of the rudder or other 30 device to be moved. Y is a crank-arm on said shaft. Z² is the cylinder of the operating-engine. C is the connecting-rod between the piston-rod and crank Y. R is the valve-case; R', the valve-spindle. B is the lever of the 35 spindle that extends into the pilot-house. S is a conical valve turning in the casing R and projecting beyond the smaller end of the casing. T is a cap covering the projecting end of the valve and secured to a spindle, k, mounted 40 in bearings on the engine. On the spindle k is a spirally-curved wing, k', the edge of which extends between adjustable lips i i' on the cross-head k'.

The valve S has circumferential grooves 1 2 3 4 45 5 6 7, and longitudinal channels m n p q, respectively communicating at one end with ports m' n' p' q', the channels m, n, and p communicating at the other end with ports e f b, and the channel q communicates with two radiating- 50 ports, c d, and channels 5, 6, and 7 to take up leakage. The casing R covers the valve S

55 nearly as far as the dotted line x, Fig. 4. The inlet-port r, Fig. 3, is opposite the groove 3. The exhaust-port s is opposite to groove 1. The right-hand port, P, of the cylinder, Fig. 3, opens opposite the groove 2, and the left-hand port, O, opens opposite the groove 4. The steam always fills the groove 3, port p', channel p, and port b, which is, however, closed when it is opposite the blank face y of the cap 60 T, Fig. 7. By turning the valve in one direction or the other the port b may be put in communication with either of two channels, u v, in the casing T. When adjusted as in Fig. 5 the steam will pass from the port b, through the 65 channel v, to the port e, along the channel m, out the port m' into the groove 2, and thence along the channel P to the right-hand end of the cylinder, throwing the piston to the left or backward. As the piston moves backward the 70 cross head is carried back, and the lips i i' act upon the wing k' so as to turn the cap T in the same direction as the valve was moved, so that the blank face y of the cap is soon brought again over the port b, closes the latter, and arrests the motion of the engine. If 75 the valve S is again turned in the same direction, the engine will start in the like direction and carry the cap farther around until the port b is again closed. The engine thus, after 80 the opening of the port to any extent, starts ahead and gradually closes the port until its action is arrested. The same result ensues if the valve is turned to bring the port b into communication with the channel u, the port n', 85 groove 4, and port O, to the left-hand end of the cylinder, and the reverse movement of the cross-head turning the cap T in the opposite direction from that described before until the blank face y closes the port b. As the valve 90 is set to bring the port b into communication with the channel v and port e the port d is brought opposite the channel u, and the steam exhausted from the left-hand end of the cylinder flows through the channel O, groove 4, 95 port n', channel n, port f, channel u, port d, channel q, port q', and groove 1 to the exhaust-pipe s. On the reverse motion the exhaust follows the port e to the channel q. The valve is set in either direction to any desired extent 100 by the pilot, who swings the lever B as may be required to effect the desired result. As

the piston moves forward or back it turns the rudder-shaft, and as the pilot can control absolutely the motion of the piston he can move and set the rudder to any position.

5 If an engine with an ordinary valve was used to move the rudder and was set in any position by cutting off the steam, the condensation of steam or leakage in the cylinder would soon draw back the piston and turn the rudder to a 10 material extent. This is avoided by the apparatus above described, as if the steam condense the drawing back of the piston and its cross-head would turn the cap so as to uncover the ports again, admit steam, and keep the rudder 15 in substantially the same position.

15 As there are no eccentrics and valve-rods on the engine, the piston can be moved back against the steam, compressing the latter, so that the rudder can turn if struck by ice, snags, &c.; but it will always resume its position, as 20 any change in the position of the piston will turn the cap T, open the ports, and admit steam until the parts are brought to the same position again.

25 It is not absolutely necessary to set the engine horizontally nor to connect it directly with the rudder. For instance, the piston-rod C may be connected to a lever, C', pivoted at C² to a stationary part of the frame, and the 30 arms of this lever may be connected by cords or chains w passing round guide-pulleys 5^c 6^c to the tiller. The movements of the rod C will thus turn the rudder.

35 As all cords or cables are liable to stretch or become slack, I provide for a limited movement of the lever B before operation on the rudder-shaft can begin. Thus the lever B may extend between set-screws on a slide, A², carried on a curve-guide, A³, and provided with a 40 pointer, 4, which extends over a graduated index, 5. The set-screws may be so adjusted that no motion will be imparted to the slide and its pointer until the slack is all taken up and the rudder begins to move, when the lever 45 will be brought into contact with one of said screws, and will move the slide and its pointer. A pivoted rack, 8, serves to secure the lever B during the adjustment of the valve. A lever, z, serves to turn the valve from the engine-room, the lever B being first disconnected.

50 It will be apparent that the ordinary ropes may be connected to the tiller and extend to the pilot-house for use in case the machinery gets out of order.

55 I do not limit myself to the precise construction of duplex valve and operating devices described and shown, as I have invented and applied for Letters Patent for other valve appliances constructed with one part to be set by hand, so as to start and continue the motion 60 of the engine until the latter automatically operates the other part and closes the steam-passage.

65 It is obvious that other devices than those described may be used for turning the valve-

shaft by the longitudinal movement of the piston-rod and by hand.

It will also be obvious that the engine described may be used for other purposes than that specially designated.

70 I claim—

1. The combination, with a rudder, of an engine connected to the rudder to operate the same and a revolving duplex-valve device, one part constructed and provided with hand setting mechanism, as specified, whereby steam may be admitted to operate the engine in either direction, and the other part connected with devices driven by the engine, and constructed to close the steam-passages after the 80 engine has moved the required distance, substantially as set forth.

75 2. The combination of the rudder-operating engine having a reciprocating piston, a valve constructed to admit steam to either end 85 of the cylinder, according to its adjustment, and another valve and appliances, substantially as described, for operating it from the engine to cut off the steam after the rudder has reached the desired position, substantially 90 as specified.

85 3. The combination of the engine, its valve device, constructed substantially as described, hand-lever extending to the pilot-house, shaft k, connected to the port-closing device, and 95 bent wing k', extending between lips i i' on the cross-head, substantially as specified.

90 4. The combination of the reciprocating engine, valve S, provided with channels and 100 ports for directing the steam to and exhausting it from the ends of the cylinder, and devices for setting said valve by hand, and a cap, T, provided with channels arranged to co-operate with those in the valve, constructed to close the steam-inlet when the cap is turned 105 in the direction in which the valve has been adjusted, and connections whereby the said cap is so turned by the engine as the latter continues its motion, substantially as set forth.

110 5. The combination of the valve-casing R, its inlet, exhaust, and cylinder ports, the valve S, having annular grooves 1 to 4, ports b, c, d, f, e, m', n', p', and q', and channels m n p q, and cap T, having channels u v, substantially 115 as set forth.

120 6. The combination, with the hand-lever B, connected to the valve device, of an index and a pointer attached to a slide arranged to be operated by the lever, and adjusting devices whereby to permit a limited motion of the lever in either direction before moving the slide, substantially as set forth.

125 7. The combination of the rudder, rudder-operating engine, pivoted lever C', guide-pulleys, and ropes connected to the tiller, substantially as set forth.

JOHN FRAZIER.
